UNITED STATES PATENT OFFICE.

FRANK FINGER, OF PITTSBURG, PENNSYLVANIA.

RAIL-JOINT.

SPECIFICATION forming part of Letters Patent No. 772,652, dated October 18, 1904.

Application filed June 22, 1904. Serial No. 213,623. (No model.)

To all whom it may concern:

Be it known that I, FRANK FINGER, a citizen of the United States of America, residing at Pittsburg, in the county of Allegheny and State of Pennsylvania, have invented certain new and useful Improvements in Rail-Joints, of which the following is a specification, reference being had therein to the accompanying drawings.

10 This invention has relation to chairs for rails and the like, and has for its object the provision of novel means whereby a section of rail may be firmly held in position upon the ties or the road-bed of a railroad.

15 Another object of my invention is to provide a chair which will be extremely simple in construction, strong and durable, and highly efficient when used, and I have so constructed my improved rail-chair as to allow for the 20 expansion and contraction of the rail-sections and at the same time prevent any lateral movement of the rail-sections mounted within the chair.

Briefly described, my improved chair consists of two members, one member being 25 adapted to be secured to the ties or road-bed and is provided with an integral fish-plate. The other member is adapted to fit within the first-named member and support the rail-sections therein, this member also being provided 30 with an integral fish-plate, and when the two members are secured together the fish-plates of each member are adapted to support the rail-sections, which are carried within the 35 chair.

All of the above construction will be hereinafter more fully described.

Referring to the drawings accompanying this application, Figure 1 is an end view of 40 my improved chair, showing a rail-section mounted therein. Fig. 2 is a side elevation of the chair, showing two rail-sections secured therein. Fig. 3 is a perspective view of one of the members comprising the chair, and 45 Fig. 4 is a perspective view of the other member comprising the chair.

Throughout the several views of the drawings like numerals of reference indicate like parts.

50 It will be seen that in Fig. 2 of the draw-

ings I have shown two rail-sections mounted within the chair, and it will be observed that my improved chair may be readily used for a rail-joint as well as for supporting a section of rail upon the tie.

When my improved chair is being used where two sections of rails are to be joined together, the chair may be supported upon one or more ties, as may be desired, and may be made of a sufficient length to span these 60 ties; but where it is used only to support the central portion of a rail the chair is made on a smaller scale and is adapted to be supported upon one tie forming the road-bed of the railroad.

The reference-numeral 1 indicates one member of the chair, and 2 the other member. The member 1 consists of the base 3, which upon its edges is provided with lugs 4, these lugs being slotted, as indicated at 5, whereby the spikes which are commonly used to secure chairs of this character upon the ties may readily engage the lugs and firmly hold the chair in the proper position upon the top of the ties. The other edge of the member 1 is 75 formed with an inwardly and upwardly extending fish-plate 6, this fish-plate being made of such shape as to conform to the contour of the web portions of the rails now used, and in the base 3 of the member 1 I form a tapered wedge-shaped slot 7 the entire length of the member, and in this tapered wedge-shaped slot is adapted to fit the tapered wedge-shaped or dovetailed enlargement 8, formed on the under face of the base 9 of the member 2. The one side of the base 9 of the member 2 is provided with an inwardly and upwardly extending fish-plate 10, which is similar to the fish-plate 6 of the member 1 and conforms to the contour of the rail-sections 80 85 which are to be mounted within the chair.

When it is desired to secure two rail-sections together or to support a rail-section upon a tie, the one rail-section is placed upon the base 9 of the member 2, the fish-plate 10 engaging the web and the under side of the head of the rail-sections, and this member 2 is then placed in the end of the member 1 and forced inwardly until it has become firmly wedged within said member.

By so constructing my improved chair it will be noted that any tendency of the rail-sections to move in one direction will cause the one member 2 of my improved chair to 5 become more firmly impinged within the member 1 and that it will be impossible for the rail-sections which have been placed in the chair to become in any manner whatever laterally displaced after the chair has been once 10 secured to the ties.

What I claim is—

1. A rail-chair composed of two sections, one section being formed with an integral fish-plate, an integral base extending beneath the 15 other section and to the outer edge thereof and being formed with a groove undercut on both sides and tapering from end to end of the section, the other section being formed with a fish-plate and a base, and resting wholly

on the base of the first-named section, and the 20 said other section being formed with a tapered and wedge-shaped section fitting in the groove in said first-named section.

2. A chair composed of two sections, each formed with an integral fish-plate and with a 25 flat base, the bases of both sections being of the same width and one resting on the other, said bases being formed with intermeshing locking members and the lowermost base being formed with integral laterally-extending 30 lugs.

In testimony whereof I affix my signature in the presence of two witnesses.

FRANK FINGER
